(57) **CLAIM**

The ornamental design for a floor brush for a vacuum cleaner as shown and described.

DESCRIPTION

The patent or application file contains at least one drawing executed in color. Copies of this patent or patent application publication with color drawing(s) will be provided by the Office upon request and payment of the necessary fee.

1.1 is a front view of a first embodiment of a floor brush for a vacuum cleaner, showing the new design;

1.2 is a rear view thereof;

1.3 is a left view thereof;

1.4 is a right view thereof;

1.5 is a top view thereof;

1.6 is a bottom view thereof;

1.7 is a front, left perspective view thereof;

1.8 is a rear, right perspective view thereof;

2.1 is a front view of a second embodiment of a floor brush for a vacuum cleaner, showing the new design;

2.2 is a rear view thereof;

2.3 is a left view thereof;

2.4 is a right view thereof;

2.5 is a top view thereof;

2.6 is a bottom view thereof;

(Continued)

2.7 is a front, left perspective view thereof; and
 2.8 is a rear, right perspective view thereof.
 The portions of the floor brush for a vacuum cleaner shown by coloring with yellow in the reproductions form no part of the claimed design.

1 Claim, 14 Drawing Sheets
